CLAIM

The ornamental design for a body shaping device, as shown and described.

DESCRIPTION

FIG. 1 is a front-right perspective view of a body shaping device;

FIG. 2 is a top view thereof;

FIG. 3 is a bottom view thereof;

FIG. 4 is a left view thereof;

FIG. 5 is a right view thereof;

FIG. 6 is a front view thereof;

FIG. 7 is a back view thereof; and,

FIG. 8 is a back-left perspective view thereof.

The broken lines depict portions of the body shaping device that form no part of the claimed design.
